Inventor;

Franklin Peale

UNITED STATES PATENT OFFICE.

FRANKLIN PEALE, OF PHILADELPHIA, PENNSYLVANIA.

PROPELLER.

Specification of Letters Patent No. 12,446, dated February 27, 1855.

To all whom it may concern:

Be it known that I, FRANKLIN PEALE, of the consolidated city and county of Philadelphia, in the State of Pennsylvania, have invented a new and Improved Method of Propelling Vessels; and I do hereby declare that the following is a full, clear, and exact description of the construction and operation of the same, reference being had to the annexed drawings, making a part of this specification, in which—

Figure 1, is a longitudinal elevation, Fig. 2, an end view, and Fig. 3, a vertical view in part.

15 The construction and operation of this mode of propelling vessels, is intended to imitate as closely as possible the natural means employed by the porpoise, and other marine animals in moving in their element, 20 and by taking advantage for this object of those forces and their resolution that can be made available through the agency of those mechanical means which are at our command.

25 Assimilated in form to the fishes tail, paddles or propellers, marked A, A, in Figs. 1, and 3, are attached to an axis or shaft marked B, capable and so constructed as to vibrate, through any portion of a revolution less than 180 degrees; the shaft B, is terminated by arms, marked K, K, at right angles to it, upon which the paddles A, A, are placed, so constructed as to allow them to change the angles which they present in 35 their action upon the water, as indicated in Fig. 3, and to be reversed, at the proper time, correspondent with and dependent upon the vibrations of the shaft B. These vibrations and angles are further assisted 40 and controlled, by another, and exterior shaft, made hollow and surrounding that marked B, which is marked C, and so constructed as to vibrate, like the first described shaft, B, through any portion of a revolution, that may be found effective, less than 180 degrees.

The different positions of the paddles A, A, at their junction with the exterior shaft C, is provided for by an universal joint 50 marked D, D, in Figs. 1, and 3, or by any other means equivalent thereto. The interior shaft B, is intended to be put in motion, and vibrated by a lever marked E, E, in Figs. 1, and 2, connected by a pitman or coupling marked F, F, with a crank marked G, G, in said figures: So in like manner the

exterior shaft C, is intended to be vibrated by a lever marked H, H, through a pitman or coupling marked I, I, put in motion by a crank, marked J, J, in the said Figs. 1, and 2. The cranks J, and G, as above described and marked, are intended to be revolved by a main shaft marked L. The cranks and levers, operating as described may be constructed of any desirable length and be made capable of adjustment, so as to cause the paddles to vibrate through any number of degrees of a revolution, or at any angle of inclination, and the speed may be so regulated as to get the best results for the object, as stated in the first paragraph of this specification.

The main shaft L, I design to be moved by a pinion with gearing or teeth, or by a belt and pulley, or by the direct action of a steam engine, or engines, or the power of an engine may be applied separately to each of the cranks J, and G. The cranks I design to construct of such lengths as to give any desirable amount of vibration to the levers H and E, or they may be made to adjust by shifting the "wrist pins" marked M, M, nearer to, or farther from the center of motion: So likewise the levers H, and E may be constructed of different proportionate lengths to the cranks J, and G, or be made capable of adjustment, for the purpose of accomplishing, as before stated, any amount of vibration, less than one half of a revolution of the axes or shafts B and C.

The cranks J, and G, may be made, and I design so to construct them that they may be set or adjusted in any position in relation to each other, for it is by this means, in part, that I design to change the angle of inclination of the paddles A to the line of progression, as exemplified by the dotted lines, marked by degrees, thus 5°, 10°, 15° in Fig. 3, and also to adjust the time, at which these changes shall be made,—but I design also, to change these angles, and time of these changes, by the adjustment of the cranks and levers, heretofore described, in a suitable manner.

By the connection of the shaft C, with the paddles A, and also by the construction of the arms K, K, and their connection with the shaft B, the paddles may be vibrated, as has been before stated through any portion of a half revolution, the paddles A, being forced to assume an angular position, or oblique to the line of progression, or mo-

tion of the vessel to be propelled, and, being reversed both in the direction of motion and in the angle of inclination, there results from this construction, a reciprocating or vibratory motion, and advantage taken of the momentum created by the displacement of the water in the direction of the motion of the paddles, and meeting the displaced and moving mass of water, by the reversed action of the paddles in the opposite direction, and thus adding the momentum of the moving or displaced mass to the propelling power first applied.

Having thus described my improved propeller, what I claim as my invention and desire to secure by Letters Patent is—

The arrangement of the paddles A, the arms K, and the shafts B, and C, arranged and operating, in the manner and for the purpose substantially as herein before described.

FRANKLIN PEALE.
